UNITED STATES PATENT OFFICE.

PIETER JOSEPH CROLLA AND PETER JOSEPH SCHMITZ, OF VOLKENBURG, NETHERLANDS, ASSIGNORS TO THE FIRM OF C. H. WINTERHOFF, OF REMScheid, GERMANY.

WRENCH.

1,051,562.

Specification of Letters Patent. Patented Jan. 28, 1913.

Application filed September 19, 1911. Serial No. 650,141.

To all whom it may concern:

Be it known that we, PIETER JOSEPH CROLLA and PETER JOSEPH SCHMITZ, subjects of the Queen of the Netherlands, and residents of Volkenburg, Netherlands, have invented certain new and useful Improvements in Wrenches, of which the following is a specification.

This invention relates to a wrench, with improved means for allowing a ratchetlike use of the same, this being obtained in that the tapered ends of a rod, which serves as handle for the wrench, are wound in spiral manner around a nut.

15 The accompanying drawing shows the improved arrangement.

Figure 1 is a plan view of the same in its use for tightening the nut, and Fig. 2 a similar view, showing the action of the wrench 20 when turned in opposite direction.

The ends of a metal rod *a*, which serves as handle for the wrench are flat and so wrought that they become thinner and thinner toward their sharp-ended extremity, the 25 same being then placed in spiral windings *b* around a nut *c*. Upon turning the wrench in the direction for tightening the nut, the

spiral windings are firmly gripped upon the nut. In the opposite direction, however, they yield in springy manner, as this is shown in Fig. 2, whereby a ratchet-like use of the wrench is possible.

Of course, the same arrangement may be provided at the other end of the rod *a*, preferably for a different size of nut. 35

The manufacture of such wrenches is very simple and cheap.

We claim:

A wrench, comprising in combination a handle with flat and gradually tapered ends 40 designed to be wound in spiral manner around nuts and adapted to be firmly attracted upon the same when tightening the nut but to yield in springy manner when turned in opposite direction, for the purpose set forth.

In testimony whereof we have hereunto set our hands in the presence of two subscribing witnesses.

PIETER JOSEPH CROLLA.
PETER JOSEPH SCHMITZ.
